ROTARY IRON STRUCTURE

Alfred F. Yoerg, Des Moines, Iowa, assignor of
one-half to Harry Schlesinger, Des Moines,
Iowa

Application July 14, 1936, Serial No. 90,558

9 Claims. (Cl. 38—74)

An object of my invention is to provide a rotary iron structure of simple, durable and inexpensive construction.

A further object is to provide a rotary laundry iron in which a sole plate is rotated by an electric motor and the sole plate is provided with a point for ironing portions of a garment which are not suitable to be ironed with the sole plate while it is rotating, and which require a point to extend up into intricate corners of the garment.

A further object is to provide a means for stopping the rotation of the sole plate so that the point is accurately alined relative to a manipulating handle member for the iron.

More particularly it is my object to provide in connection with an iron having a rotary sole plate a means for stopping the sole plate in a predetermined position relative to the manipulating handle member for the iron, which means mechanically disconnects the motor from the sole plate, de-energizes the motor and positively stops the sole plate in only one possible position.

A further object is to provide an improved construction for rotatably mounting a sole plate relative to a manipulating handle member of a rotary iron.

Still another object is to provide means of connection between a sole plate and the manipulating handle member of the casing whereby the sole plate is rotatably mounted relative to the casing without any possibility of wobbling of one relative to the other, the connection being such as to involve a minimum of friction during operation.

With these and other objects in view, my invention consists in the construction, arrangement and combination of the various parts of the device, whereby the objects contemplated are attained, as hereinafter more fully set forth, pointed out in my claims, and illustrated in the accompanying drawings, in which:

Figure 1 is a plan view of a rotary laundry iron embodying my invention, a portion thereof being broken away to show constructional details.

Figure 2 is a side elevation of the iron on an enlarged scale, a portion thereof being broken away and other portions shown in section to illustrate constructional features.

Figure 3 is a sectional view on the line 3—3 of Figure 2, looking downwardly and illustrating the sole plate and the mechanism mounted thereon in plan elevation.

Figure 4 is a sectional view on the same line 3—3 of Figure 2 looking upwardly and showing the manipulating handle member and the mech-

anism mounted thereon in bottom plan elevation.

Figure 5 is a similar sectional view on the line 5—5 of Figure 2 illustrating a clutch control mechanism.

Figure 6 is a sectional view on the line 6—6 of Figure 2, showing a thermostat control arrangement.

Figure 7 is an enlarged view of the upper portion of Figure 2 showing a projection and notched connection between the sole plate and a driven gear for rotating it.

Figure 8 is an enlarged sectional view on the line 8—8 of Figure 3.

Figure 9 is a further enlarged perspective view of a portion of a clutch projection shown in side elevation in Figure 8.

Figure 10 is an enlarged sectional view on the line 10—10 of Figure 6 showing the thermostat control.

Figure 11 is a perspective view of a brush and follower member used in conjunction with a commutator in my rotary iron.

Figure 12 is an electro diagrammatical view of the iron.

On the accompanying drawings I have used the reference numeral 10 to indicate a sole plate. The sole plate 10 is provided with a cover member 16 and the two are rotatably mounted relative to a casing 56 in the following described manner.

On the cover 16 I provide an inner ball race 13 and on the casing 56 an outer ball race 15. These of course, are annular and interposed between them is an annular row of balls 17, providing a connection between the sole plate 10 and the casing 56, which permits relative rotation with a minimum of friction and wear.

During assembly, in order to position the balls 17 between the races 13 and 15, they are fed to position between the races through a bore 19 in the race 15, after the two races are positioned approximately in alinement with each other. After the races have been filled with balls, a plug 21 is inserted to retain them in position. This plug is provided on its inner end with a face 23 coincident with the contour of the ball face of the race 15.

The sole plate 10 may be of suitably hollowed-out construction to receive a heating element 12 in the usual manner. The heating element has terminal wires 14 which extend to a connector 16 and a thermostat A respectively. From the thermostat A a wire 18 extends to a connector 20. The connectors 16 and 20 are adapted to

receive prongs 22 which are electrically connected with collector rings 24.

The thermostat A may be of any suitable construction. I have illustrated it in Figure 10 as comprising a bimetal contact bar 26 adapted for making contact with an adjustable bar 28. The bar 28 is adjusted in position by an adjusting screw 30 having a lever 32. The lever 32 may be swung to different adjusted positions by a link 34 connected with a second lever 36. The lever 36 is secured to a rock shaft 38 terminating in a control knob 40. The knob 40 is located in a point portion 11 of the sole plate 10.

Current is supplied from a supply cord 42 to the collector rings 24 through arcuate brushes 44 formed of carbon or the like, and having suitable flexible leads or pigtails 46 connected with the wires 42. The brushes 44 are urged to engage the collector rings 24 as shown in Figure 2 by a follower plate 48 and springs 50. The follower plate 48 has a pair of pins 52 received in the springs 50 to prevent them from buckling. The brushes 44 are mounted in arcuate bores 54 of a casing member 56.

For rotating the sole plate 10 I provide an electric motor 58 mounted on the casing 56 and retained in position by a clamp 60. The shaft of the motor is provided with a worm 62 (see Figure 1) which meshes with a worm gear 64. The worm gear 64 is secured to a shaft 66 to which is also secured a pinion 68 (see Fig. 4). The worm 62 and the worm gear 64 are suitably encased in a housing 70, while the pinion 68 is encased in a housing 72.

An annular mounting ring 74 is mounted on the sole plate 10, or rather on a cover 76 for the sole plate. The ring 74 retains a ring gear 78 in position relative to the cover 76, yet permits rotation of the gear relative thereto. The gear 78 meshes with the pinion 68.

I provide a clutch connection between the ring gear 78 and the sole plate 10 in the form of a rotatable stud 80 journaled in a bore 82 of the cover 76, and having an eccentric wing 84 to engage in one of a series of four notches 86 formed on the internal diameter of the ring gear 78. The stud 80 normally assumes the position shown in Figures 3, 5 and 8 with the wing 84 in one of the notches 86, due to the action of a spring 88. This spring tends to rotate a lever 90 in a clockwise direction, thereby rotating a lever 92 also in a clockwise direction through the medium of a link connection 94, the lever being limited in position by striking one end of a slot 96. Obviously when the lever is swung counter-clockwise, as in Figure 5, the lever 92 will also be swung counter-clockwise which will move the wing 84 from the dotted position of Figure 7 to the full line position shown therein, the purpose of which will hereinafter be described.

On the side of the casing 56 I provide a boss 98. A stop pin 100 is slidably mounted therein and adapted for contacting with the upper face 102 of the cover 76 and to enter a notch 104 therein when such notch registers with the pin as shown by dotted lines in Figure 2. The stop pin 100 is urged upwardly in any suitable manner as by a leaf spring 101, and is adapted to be actuated downwardly by a control rod 106 having a rounded head 108 for wedging between a stop plate 110 and the rounded upper end of the pin 100.

The control rod 106 is adapted to be slid in one direction by a button 112, and in the other di-

rection by a button 114 on a pivoted lever 116. The head 108 is connected with a switch lever 117, this switch being in circuit with the motor 58, as shown in Figure 12. A switch 118 on the opposite side of the casing 56 is provided for the heating element 12.

The lever 116 is pivoted on a handle bolt 120 which extends through a handle 122. The handle is provided for manipulating the iron and is supported relative to the casing 56 by a pair of arms 124.

Practical operation

In the operation of my iron, the switch 118 can be closed for closing the circuit through the heating element 12, for thus heating the sole plate 10. Thereafter the temperature of the sole plate is automatically controlled by the thermostat A, depending on its setting. The button 114 is then pressed for moving the lever 116 to the dotted position in Figure 2, whereupon the switch 117 is turned on for energizing the motor 58, and the pin 100 is raised out of the notch 104 which, as will hereinafter appear, effects a clutch connection between the ring gear 78 and the sole plate 10. With the sole plate 10 in operation, the operator can iron a greater area of clothing in less time than by using a stationary sole plate, as a greater area of the garment is gone over while the sole plate is in rotation than if it were stationary during the passage of the iron across the garment.

There are many places on articles of clothing where it is undesirable to use the sole plate while rotating, particularly places which have to be entered with a point of the iron. Accordingly I provide the point 11, and when it is desired to use the point for the purpose above outlined, it is, of course, desirable to stop it in a predetermined position relative to the handle 112. This is accomplished by pressing on the button 112 which first moves from the dotted position to the full line position of Figure 2, and in so doing moves the stop 100 from its upper dotted position to its intermediate full line position contacting with the upper surface 102 of the cover 76. In this position it is projected into the path of the outer end of the lever 90, which lever strikes it and is then held from further rotation by the stop pin. This produces a movement of the lever 90 counter-clockwise relative to the sole plate 10 when viewed as in Figure 5, which rotates the wing 84 of Figure 7 from the dotted position to the full line position in which latter position it is disengaged from the notch 86 in which it is seated. This permits the ring gear 78 to continue to rotate while the sole plate 10 will rotate, due only to its momentum.

The notch 104 is so related in position to the lever 90 that it will be about in the position of Figure 2 when the clutch connection has been finally disengaged. Momentum will then carry it to the dash line position, which will permit the pin 100 to drop to its lower limit of movement, also shown by dash lines, such dropping thereof being effected by reason of the operator still having his thumb on the button 112 and attempting to push the rod 106 inwardly to shut off the motor by moving the switch lever 117 to its open circuit position. Therefore the sole plate 10 will be stopped in a predetermined position, or with its point 11 in a predetermined position relative to the handle 122, and the motor will be simultaneously de-energized, as it will no longer be needed, even though disconnected.

from the sole plate through the clutch connection described.

Returning now to subsequent rotation of the sole plate 10, it will be obvious that when the 5 button 114 is pressed upon, the switch 117 will be turned on and the head 108 will be moved from its left dash line position in Figure 2 to its right dotted position, whereupon the pin 100 will be raised first out of the notch 104 and then 10 out of the way of the lever 90. The spring 88 will then swing the lever 90 toward the position of Figure 5, whereupon the edge of the wing 84 will engage the inner surface 79 of the ring gear 78 until one of the notches 86 registers there- 15 with, whereupon the spring 88 will swing the lever 90 further to its full line position in Figure 5. This will place the wing 84 in the notch as shown by dotted lines in Figure 7, whereupon the sole plate will be connected with the motor 58 20 and thereafter rotated thereby until the control button 112 is again pushed inwardly.

Some changes may be made in the construction and arrangement of the parts of my device without departing from the real spirit and purpose of my invention, and it is my intention to cover by my claims any modified forms of structure or use of mechanical equivalents which may be reasonably included within their scope.

I claim as my invention:

30 1. In a rotary iron of the character described, a manipulating handle member, a sole plate rotatably mounted relative thereto, means for heating said sole plate, means for rotating said sole plate and means for stopping said sole plate 35 in a predetermined position relative to said manipulating handle member.

2. In a rotary iron of the character described, a manipulating handle member, a sole plate rotatably mounted relative thereto, means for heating said sole plate, means for rotating said sole plate, a pointed extension on the periphery of said sole plate and means for stopping the rotation of said sole plate with said point in a predetermined position relative to said manipulating 45 handle member.

3. In a rotary iron of the character described, a manipulating handle member, a sole plate rotatably mounted relative thereto, means for heating said sole plate, a motor operatively connected with said sole plate for rotating it and means for simultaneously disconnecting said motor from said sole plate and de-energizing said motor and stopping said sole plate in a predetermined position relative to said manipulating 55 handle member.

4. In a rotary iron of the character described, a manipulating handle member, a sole plate rotatably mounted relative thereto, said sole plate having a depression, a movable stop lug on said 60 handle member, means for heating said sole plate, a motor operatively connected with said sole plate for rotating it and means for disconnecting said motor from said sole plate, de-energizing said motor and engaging said stop lug 65 with the depression of said sole plate to stop it in a predetermined position relative to said manipulating handle member.

5. In a rotary iron of the character described, a manipulating handle member, a sole plate 70 mounted relative thereto, an electric motor on said handle member for rotating said sole plate,

a clutch connection between said motor and said sole plate, a switch for said motor and a controller for said clutch connection and motor, said controller being connected with said switch and said clutch connection and movable to a predetermined position for simultaneously disengaging said clutch connection and opening said switch. 5

6. In a rotary iron of the character described, a manipulating handle member, a sole plate 10 mounted relative thereto, an electric motor on said handle member for rotating said sole plate, a clutch connection between said motor and said sole plate, a switch for said motor and a common control means for said clutch connection, 15 motor and sole plate, said common means simultaneously disengaging said clutch, de-energizing said motor and stopping said sole plate relative to said manipulating handle member.

7. In a rotary iron, a manipulating handle member, a sole plate, a pointed extension on the periphery of the sole plate, said sole plate being rotatably mounted relative to said manipulating handle member, an electric motor on said handle member for rotating said sole plate, a clutch connection between said motor and sole plate, a switch for said motor and a controller for said clutch connection and motor, said controller, when moved to one position disengaging said clutch and then de-energizing said motor and 20 engaging said sole plate to stop the rotation thereof with said pointed extension in a predetermined position relative to said handle member. 25

8. In a rotary iron, a manipulating handle 30 member, a sole plate rotatably mounted relative thereto, an electric motor on said handle member, a driven member rotatably mounted on said sole plate and operatively connected with said electric motor, said driven member having a plurality of notches, a projection on said sole plate adapted to extend into one of said notches for operatively connecting said driven member with said sole plate, a switch for said motor and a movable controller for said projection and motor, 40 said controller in one position thereof, removing said projection from the notch in which it is seated and then de-energizing said motor. 45

9. In a rotary iron, a manipulating handle member, a stop lug carried thereby, a sole plate 50 rotatably mounted relative thereto and having a depression, a pointed projection on the periphery of said sole plate, an electric motor on said handle member, a driven member rotatably mounted on said sole plate and operatively 55 connected with said electric motor, said driven member having a plurality of notches, a projection element on said sole plate adapted to extend into one of said notches for operatively connecting said driven member with said sole plate, a switch for said motor and a movable controller for said projection element, motor and sole plate, said controller, when positioned for operation, disengaging said projection from the notch of said driven member in which it is seated, de-energizing said motor and engaging said stop lug with said depression of said sole plate to stop 60 rotation thereof with said pointed projection in a predetermined position relative to said handle member. 65

ALFRED F. YOERG.
